HARRY GOLDENBERG, OF NEW YORK, N. Y.

TUCK-LOOP-SECURING DEVICE.

1,171,513.

Specification of Letters Patent. Patented Feb. 15, 1916.

Application filed May 14, 1915. Serial No. 28,158.

To all whom it may concern:

Be it known that I, HARRY GOLDENBERG, a citizen of the United States, residing at New York, in the county of New York and State of New York, have invented certain new and useful Improvements in Tuck-Loop-Securing Devices, of which the following is a specification.

My invention relates to improvements in tuck loop securing devices, and the object of my improvement is to provide means in the form of a clenching device for securing tuck loops of leather or webbing to the belts without stitching, and by means that are effective and reliable.

In the accompanying drawing: Figure 1 is a front elevation of part of a belt and a pair of tuck loops secured by means of my invention. Fig. 2 is an edge view of the same. Fig. 3 is a rear elevation of part of the same. Fig. 4 is a sectional view on the line $x-x$ of Fig. 1. Fig. 5 is a rear elevation of the tuck loop. Fig. 6 is a plan view of the blank for the clenching device. Fig. 7 is a side elevation of the same with the ends bent up to fit the belt. Fig. 8 is a perspective view of the same.

The belt 10 shown in Fig. 1 is provided with two tuck loops 11, secured by means of my clenching device 12. The tuck loops 11 are ordinary and comprise a strip of leather or fabric bent into loop form of proper size and shape to inclose the body of the belt 10 and to house the free end thereof, the ends 13 of the said tuck loop being brought into abutment and secured together in some suitable manner, as by a metal clip 14, so that the tuck loop is in the form of an endless structure. As is usual in belt construction, the belt 10 is looped around the bar 15 of the buckle 16 and the tuck loops 11 are secured to the belt 10 adjacent the buckle 16. In securing the tuck loop and buckle to the belt as mentioned the belt is slipped through the loop or loops 11, the number being as desired, the belt is bent around the bar 15 of the buckle 16, and the belt end 17 is brought back along the rear face of the opposed portion of the belt body, and also at the rear of the tuck loops 11. Accordingly, a portion of the tuck loop 11 is positioned between the body of the belt 10 and the opposed overlapping end portion 17, and the particular part of the tuck loop 11 that is so positioned between the opposed parts of the belt 10 is the end portion com-

prising the opposed ends 13, 13, and clip 14 that holds these together. The outer portion 22 of the tuck loop 11 serves as the tuck loop proper and is separated from the body portion 10 of the belt by a space such as to allow for tucking the free end of the belt therein as usual. In fact the features so far described are essentially ordinary.

My invention resides in the clenching device 12 and the manner of using the same for positioning the tuck loops on the belt and for preventing relative longitudinal movement of one to the other, and as mentioned, to do this without the use of stitching. The said clenching device or clencher 12 is in the form of a closed loop having prongs 18 at the ends, and when used in the manner to be described serves to positively secure the tuck loop in position.

In detail, the clencher 12 comprises a pair of side bars 19 cross-connected at the ends by cross-bars 20, and the teeth or prongs 18 extend outwardly from the said cross-bars 20. The side bars 19 are separated by an opening 21 that is of a width such as to conveniently slip over the outer portion 22 of the tuck loop 11 and the length of the side bars 19 and opening 21 corresponding thereto is appreciably greater than the width of the belt 10. The end portions are bent at right angles to the middle portion as shown in Fig. 7 and a sufficient distance apart so that the belt will fit therebetween. Also the prongs 18 are bent inwardly. In this condition the clencher 12 is ready to be applied to the belt, and the same is effected in the following manner: The tuck loop 11 having been applied to the belt in the manner described, the tuck loop proper 22 is positioned at the front of the belt and the tuck loop ends 13 are positioned between the two layers of the belt 10. The clencher 12 is slipped over the belt 10 from the front toward the rear, the tuck loop proper 22 passing through the opening 21, and therefore, one side bar 19 being on each side of the tuck loop 11. In this position the upturned end portions of the side bars 19 cross the lateral ends of the tuck loop 11. The end portions of the clencher 12 are then folded inwardly

over against the rear face of the end portion 17 of the belt 10 and the prongs 18 are driven into the material of the said end portion 17 of the belt, thus effecting the securing desired.

As shown and described, the clencher 12 is

of skeleton construction, the bars of which the same is constructed being relatively narrow. Furthermore, because of the narrowness of the bars mentioned they are relatively inconspicuous, and the portion that is exposed at the front is in the form of a narrow line or one line effect on each side of the tuck loop, somewhat after the manner of the usual lines of stitching. The clencher shown is adapted for use with belts differing appreciably in width. In any case the side bars should be of sufficient length to extend across the front face of the belt, over the lateral edges, and a slight distance inwardly from the said edges on the rear portion of the belt structure.

I claim as my invention:—

In combination, a belt having overlapping portions forming a loop, a buckle having a

bar engaged with the said loop, a tuck loop formed as an endless structure, having a portion of its length positioned between the said overlapping portions, and a clenching device, the said clenching device comprising a pair of side bars positioned one on each side of the said tuck loop, each extending across the front face of the said belt, over the lateral edges thereof, and inwardly from the said edges for an appreciable distance across the rear face of the said belt, and cross-bars connecting the ends of the said side bars at the rear face of the said belt, and prongs on the said cross-bars embedded in material of the said belt.

HARRY GOLDENBERG.
